**TOWABLE SLED FOR SNOWMOBILES,
BOATS AND THE LIKE**

Merlin Johnson, 300 N. 4th St.,
Clear Lake, Iowa 50428

Filed Feb. 20, 1973, Ser. No. 334,111

Term of patent 14 years

Int. Cl. D12—14

U.S. Cl. D12—11

Fig. 5

Fig. 6

FIG. 1 is a perspective view of a towable sled for snowmobiles, boats and the like showing my new design;

FIG. 2 is an enlarged scale top plan view thereof;

FIG. 3 is a front elevational view thereof;

FIG. 4 is a rear elevational view thereof;

FIG. 5 is a typical side elevational view thereof; and FIG. 6 is a bottom plan view thereof.

I claim:

The ornamental design for a towable sled for snowmobiles, boats and the like, as substantially shown.
